UNITED STATES PATENT OFFICE.

WILHELM G. HENNINGS, OF CHICAGO, ILLINOIS, ASSIGNOR OF ONE-HALF
TO HERMAN HEIN, OF SAME PLACE.

REGISTER FOR MONEY-DRAWERS.

SPECIFICATION forming part of Letters Patent No. 326,114, dated September 15, 1885.

Application filed December 20, 1884. (No model.)

To all whom it may concern:

Be it known that I, WILHELM G. HENNINGS, a subject of the Emperor of Germany, residing at Chicago, in the county of Cook and State of Illinois, have invented certain new and useful 5 Improvements in Registers for Money-Drawers, of which the following is a specification, to wit:

This invention relates to an improvement 10 in registers for money-drawers; and it consists in certain peculiarities of the construction and operation of the same, substantially as will be hereinafter more fully set forth and claimed.

15 In order to enable others skilled in the art to which my invention appertains to make and use the same, I will now proceed to describe its construction and operation, referring to the accompanying drawings, in which—

20 Figure 1 is a perspective view of a money-drawer with my device attached, and Fig. 2 is a view of the interior mechanism of the register.

A represents a money-drawer of any desired construction sliding in suitable ways or guides beneath the counter A'. Upon the side of this drawer I secure a small case or frame B, in which are two drums, B' B', connected by a band of paper, C, which is transferred from one drum to the other as the device is operated. The upper side of the case B is formed with two slots, b' b', through one of which the paper band C passes out, and back through the other on its way from one 35 spool to the other, and thus leaves a short section exposed for a purpose presently seen. One of the drums or spools B is provided with a series of ratchet-teeth, c, and a retaining-pawl, c', which prevents any backward motion; and upon the pivot b² of this 40 spool is hung an arm, D, carrying a second pawl, d, which feeds the spool forward as the arm is moved.

To the lower end of this arm D is hinged 45 a trigger, D', which contacts with and moves the arm forward in one direction and swings freely in the opposite direction, and which passes through a slot in the bottom of the case to the outside.

50 The arm D is provided with a spring, e, and the trigger D' with a spring, e', which returns them to their places when moved.

One side of the case is removable, and is secured in place by means of an ordinary

lock, the key of which is inserted in a key-hole, f, (shown in Fig. 1;) and upon the under side of the counter is an arm or stop, G, which engages and moves the trigger as the drawer is drawn out.

In operation the amount of change in the 60 drawer is noted in pencil or by similar means upon that portion of the paper tape which is exposed upon the outside of the case. When money is taken in by a clerk he draws out the drawer, and in doing so the trigger strikes 65 the projection G and feeds forward the tape till the pencil-note is drawn into the case and a blank section exposed. The amount taken in is entered again before the drawer is closed, and in plain view of the customer, 70 which prevents a false entry. At the close of business the owner unlocks and removes the side of the case, and taking out the spools adds the entries, the full amount of which must correspond with the cash in the drawer, 75 if all is correct, and thus any theft of the clerks is prevented.

The device is simple, and, being readily attached to any money-drawer, is an effectual check on dishonest employés. As shown in 80 Fig. 1, a small glass, h, may be inserted in the counter, through which the tape and its entry may be readily seen when the drawer is closed.

Having thus fully described my invention, 85 what I claim as new, and desire to secure by Letters Patent, is—

The combination, with a money-drawer sliding in guides beneath a counter, and an arm or stop secured to said counter, of the 90 case B, having one side removable, and formed with the slots b b', the two spools B B', connected by a tape, C, passing through said slots, a retaining-pawl, c', engaging teeth c on one of said spools, a spring-actuated arm, 95 D, hinged in the case, and having the feeding-pawl d, and the spring-actuated trigger D' on the end of this arm, projecting through the case and contacting with the arm or stop on the counter, substantially as and for the purpose set forth.

In testimony whereof I affix my signature in presence of two witnesses.

WILHELM G. HENNINGS.
